(57) CLAIM

The ornamental designs for a combined game coin and package, as shown and described.

DESCRIPTION

FIG. 1 is a perspective view of the combined game coin and package of the present invention.

FIG. 2 is a front view of the combined game coin and package of FIG. 1.

FIG. 3 is a rear view of the combined game coin and package of FIG. 1.

FIG. 4 is a right side view of the combined game coin and package of FIG. 1, the left side view being identical thereto.

FIG. 5 is a top view of the combined game coin and package of FIG. 1.

FIG. 6 is a bottom view of the combined game coin and package of FIG. 1; and,

FIG. 7 is a perspective tear-away view of the combined game coin and package of FIG. 1.

In the drawings, the broken lines depict unclaimed subject matter only and form no part of the claimed design.
